ROLLER COATING MACHINE

William E. Shehan, Los Angeles, Calif.

Application March 6, 1934, Serial No. 714,212
Renewed November 20, 1935

6 Claims. (Cl. 91—50)

This invention relates to a machine for coating slats with fluent material such as paints, lacquers, varnishes and the like. The embodiment disclosed herein is adapted for applying a coating to slats for Venetian blinds. It will be understood however, that the specific embodiment is merely illustrative of the invention. Roller coating machines have been used for the purpose of coating slats, but in machines in current use the coating material has commonly been applied directly to the distributing rollers from supply wells. The result is that a surplusage of the coating material has been applied to the distributing rollers. As the slat emerges from between the rollers, a blob of coating material has been left on the tail end of the slat, and it has been the practice to cut off the end carrying the blob causing additional labor and wastage of wood. Furthermore, due to the surplusage, if the slat contains holes or indentations a film of the coating material is spread over the mouth of the indentation or hole. The surface tension then causes breaking of the film and resultant blobs at the lips of the mouths. Slats for Venetian blinds are formed with holes for passage of control cords in the assembled blind. In order to avoid formation of blobs at the edges of the holes, it has been the practice to cut the holes after the slat has been coated on its faces. The walls of the holes thus cut are then coated by hand. This results in added labor.

The primary object of this invention is to provide a roller coating machine which will apply a coating to slats having indentations or holes and will not leave blobs of coating on the faces.

These objects together with other objects and corresponding accomplishments are obtained by means of the embodiment of my invention illustrated in the accompanying drawings, in which: Fig. 1 is a side elevational view of a coating machine with a part of the bed broken out to make the view more compact; Fig. 2 is a plan view of the structure shown in Fig. 1; Fig. 3 is an enlarged side elevational view of the roller unit, the side coating rollers being omitted and parts being shown in sectional elevation; Fig. 4 is an end elevational view of the unit shown in Fig. 3; Fig. 5 is an enlarged plan view of the side coating roller assemblage; Fig. 6 is a side elevational view of the assemblage shown in Fig. 5; Fig. 7 is an end elevational view of a fragment of the roller unit showing the adjustable bearing mounting; and Fig. 8 is a sectional view as seen on the plane indicated by 8—8 in Fig. 7.

Referring with more particularity to the draw-

ings, a frame 10 is shown constructed of suitable bars. This frame 10 supports a roller frame 11 having side columns 12 at the head end and side columns 13 at the tail end. A shaft 14 is journaled in bearings fixed to the side columns 12 and overhangs the frame 11 having a feed roller 15 fixed thereto. A shaft 16 is journaled in bearings fixed to the side columns 12 above shaft 14 and has a distributing roller 17 fixed thereto and disposed in frictional engagement with feed roller 15. Roller 17 is preferably formed of a composition such as sponge rubber having resiliency, such compositions being well known in the art. A bearing mounting 18 is secured to columns 12 by means of bolts 19 extending through elongated slots 20. An adjusting screw 21 is threadedly secured to a projection on mounting 18 and to the top rail 12a of the column for adjusting the elevation of mounting 18. Fixed to mounting 18 are bearings, one for a shaft 22. A distributing roller 23 is mounted on the overhanging end of shaft 22 and forms a companion for roller 17 which is spaced therefrom. A second set of bearings is fixed to mounting 18 and journaled therein is a shaft 24 carrying a feed roller 25 which is fixed thereto. Thus, shafts 22 and 24 are mounted on mounting 18 as a unit and may be raised and lowered so that distributing roller 23 may be adjusted to or from roller 17 and thereby accommodate the space between them for transfer of a desired amount of coating material. Rollers 17 and 23 are for the purpose of coating the faces of slats passed between them.

A well 26 in the form of a box is disposed below roller 25 and is kept filled with fluent coating material to a level such that feed roller 15 dips therein and carries a film of coating to distributing roller 17. The feed roller 15 and distributing roller 17 being in contact any surplus coating material is expressed. A well 27 for delivering coating material to feed roller 25 is disposed above the latter. An orifice for outlet of coating material is controlled by an adjustable needle valve 28. The coating material passing from well 27 to feed roller 25 is spread longitudinally over the latter by the expressing action of feed roller 25 and distributing roller 23.

Journaled in bearings on columns 13 are shafts carrying conveyor rollers 29 and 30 with the space between them alining with the space between rollers 17 and 23. Pinions, one indicated by 31 are fixed to ends of the conveyor roller shafts and are meshed with one another. Pinions 33 and 34 are journaled on columns 13 and meshed with the aforesaid pinions. Secured to

each of the pinions is a sprocket wheel. Shafts 14, 16, 22 and 24 have sprocket wheels secured to the ends thereof and the sprocket wheels are geared together by sprocket chains 35, 36, 37 and 38. The shaft carrying conveyor roller 28 is extended to a gear box 39 mounted on a driving motor 40. The gearing is of such a character that all rollers are positively driven to have the same peripheral speeds. Rollers 29 and 30 are preferably made of hard rubber to firmly grip a slat and convey it to the rollers 17 and 23.

In order to conveniently deliver slats to the conveyor rollers, the frame is provided with a bed 41 formed by a slotted bar and a table 42 at one side. The bed 41 has its upper surface aligned with the spaces between rollers 17, 23 and rollers 29, 30. Guide posts 43 are fixed to the bed 41 and define a space in which a slat may be guided to the conveyor rollers. Slot 44 in the bed 41 is formed to slidably receive a shoe on a push carriage 45. A rod 46 extends into a bore in carriage 45 and is fastened thereto by a set screw 47. By sliding the rod forwardly and backwardly, carriage 45 is moved to and from the conveyor rollers. Rod 46 is pivotally secured at its head end 48 to a lever arm 49 which is pivotally mounted at its lower end to a bracket 49' fixed to frame 10. By rocking the lever arm 49 rod 46 may be moved longitudinally of itself. Pivotally mounted at 48" on the frame 10 is a pedal 49 having an arm 50 fixedly secured thereto. Arm 50 is pivotally secured to arm 48 by a link 51. A tension spring 52 tends to hold rod 46 with the push carriage 45 in its outermost position. Depression of pedal 49 will cause movement of push carriage 45 toward the conveyor rollers. Release of the pedal allows spring 52 to restore carriage 45 to its outermost position. A number of slats may be placed on table 42. A slat 5 is transferred from the table to bed 41. The motor 40 being in operation, the machine operator depressed pedal 49 thereby causing the selected slat to be pushed forward for engagement by the conveyor rollers 29 and 30. The conveyor rollers then move the slat between the face rollers 17 and 23 which transfer a layer of coating material to the faces of the slat. The slat is finally discharged by the face rollers.

Means is provided for coating the sides of the slat during its travel. There is a side coating mechanism 32 on each side of the path of travel of the slats through the machine. As these mechanisms are duplicates except as to reversal of positions, it will be sufficient to describe only one. An arm 53 is pivotally secured to frame 11. A screw 54 is also secured to the frame and passed through a projection on the arm. A wing nut 55 is threaded on screw 54 and may engage arm 53. Pivotally mounted on the free end of arm 53 are roller arms 56 and 57 with spring means tending to close them on one another. Journalled on the ends of arms 56 and 57 are rollers 58 and 59. Intermediate rollers 58 and 59 is an idler roller 60 journalled on the pivot pin for arms 56 and 57. Roller 58 engages an end of face roller 23 and carries coating material therefrom to roller 60 and thence to side distributing roller 59. Wing nut 55 is adjusted to maintain roller 59 in contact with a side of a slat and roller 58 in contact with face roller 23. Thus, coating material will be distributed to the sides of a slat, so that in the travel of the latter, the sides and faces will be coated uniformly.

It will be noted that the top rollers 23 and 25 may be run dry and the bottom rollers 15

and 17 used for coating one side of a slat. This permits a slat to be coated with different colors on opposite faces. A slat may be run through the machine to coat one face with one color, then the color changed and the slat turned over and coated on the other face.

What I claim is:

1. In a slat coating machine, the combination of a frame: a face roller journalled on said frame, a feed roller journalled on said frame and frictionally engaged with said face roller for carrying coating material to the latter, supply means for carrying coating material to said feed roller; a companion face roller journalled on said frame, a feed roller journalled on said frame and frictionally engaged with said companion face roller, supply means for carrying coating material to said last mentioned feed roller, said face rollers being spaced to accommodate the travel of a slat therebetween; driving means gearing all of said rollers together; means to direct a slat for engagement between said face rollers; side coating roller mechanisms, one mounted at each end of a face roller, each mechanism comprising a roller carrier mounted on said frame for lateral adjustment with respect to said slat, a side feed roller journalled on said carrier and frictionally engaged with an end of a face roller, an intermediate roller journalled on said carrier and frictionally in train with said side feed roller, and a side distributing roller journalled on said frame and frictionally in train with said intermediate roller, said side distributing roller being resiliently mounted to be engaged with a side of a slat. 30

2. In a slat coating machine, the combination of a frame: a face roller journalled on said frame, a feed roller journalled on said frame and frictionally engaged with said face roller for carrying coating material to the latter, supply means 40

for carrying coating material to said feed roller; a companion face roller journalled on said frame, a feed roller journalled on said frame, and frictionally engaged with said companion face roller, supply means for carrying coating material to said last mentioned feed roller, said face rollers being spaced to accommodate the travel of a slat therebetween; driving means gearing all of said rollers together; a bed having a surface aligned with the space between said face rollers for slidably supporting a slat, a carriage riding on said bed and having an abutment to engage the end of a slat, means to move said carriage and slide a slat engaged therewith toward said face rollers; side coating roller mechanisms, one mounted at each end of a face roller, each mechanism comprising a roller carrier mounted on said frame for lateral adjustment with respect to said slat, a side feed roller journalled on said carrier and frictionally engaged with an end of a face roller, an intermediate roller journalled on said carrier and frictionally in train with said side feed roller, and a side distributing roller journalled on said frame and frictionally in train with said intermediate roller, said side distributing roller being resiliently mounted to be engaged with a side of a slat. 50

3. In a slat coating machine, the combination of a frame: a face roller journalled on said frame, a feed roller journalled on said frame and frictionally engaged with said face roller for carrying coating material to the latter, supply means for carrying coating material to said feed roller; a bearing mounting, a companion face roller journalled in said mounting, a feed roller journalled 70

frictionally engaged with said face roller for carrying coating material to the latter, supply means for carrying coating material to said feed roller; a bearing mounting, a companion face roller journalled in said mounting, a feed roller journalled 75
